PIPE COATING APPARATUS

Albert G. Perkins, Warsaw, N. Y.

Application May 22, 1936, Serial No. 81,275

7 Claims.

(Cl. 91—44)

This invention relates to an apparatus which has been designed more particularly for applying a protective coating or lining to the inner walls of pipes, conduits and the like.

5 It has for one of its objects to provide an efficient apparatus of this character having simple, reliable and inexpensive means for effecting an uninterrupted and continuous uniform feed of the coating material to the distributing head of the 10 machine.

Another object of the invention is the provision of a pipe coating machine having improved means for centrifugally distributing the material against the pipe wall.

15 In the accompanying drawing:—

Figure 1 is a side elevation of my improved coating apparatus, the same being shown within a pipe line for treating the interior wall thereof with a protective coating. Figure 2 is an enlarged fragmentary longitudinal section of the 20 discharge end of the machine showing the distributor head and blade structure. Figure 3 is a cross section taken substantially in the plane of line 3—3, Figure 2. Figure 4 is an enlarged fragmentary side elevation of the ported discharge end 25 of the feed tube or conduit. Figure 5 is a fragmentary perspective view of a slightly modified construction of distributing blade.

Similar characters of reference indicate corresponding parts through the several views.

30 While my apparatus may be employed for coating different kinds of work, it has been primarily designed for treating the inner walls of steel pipe lines with a protective coating, such for example, as a plastic material as concrete. To this end the apparatus consists generally of a carriage which is adapted to be propelled through the pipe line and which carries the working parts of the apparatus, such working parts comprising essentially a hopper or container for the coating material having a conduit or feed pipe connected therewith, means for conveying the material from the hopper through the conduit, a dispensing or discharge head into which the material is delivered and from which it is discharged by centrifugal 45 force onto the pipe wall, and means for troweling the material after it has been applied to the pipe wall.

Referring now to the drawing, 10 indicates a 50 section of the steel pipe line through which my apparatus travels during the coating of the inner wall with concrete or like plastic or semi-solid material. The carriage may consist of a body 11 provided at one end with traction or supporting wheels 12 and provided at its opposite end with a

steering wheel or caster 13 mounted on a swiveling fork 14. Motion is transmitted to the traction wheels from an electric or like motor 15 suitably mounted on the carriage-body, the drive from the motor being through the medium of a gear train of usual construction. For the purpose of this description, the wheels 12 may be considered as mounted at the rear end of the machine and the steering wheel 13 at the front end thereof.

5 Disposed at the front end of the machine is a feed hopper or container 16 for the coating material and extending rearwardly therefrom is a feed conduit or passage 17 which is disposed lengthwise and centrally of the machine and approximately axially of the pipe 10. A screw conveyor 18 or like device is provided in the hopper and feed conduit for positively feeding the material from the hopper through the conduit to the discharge end of the same. This screw conveyor may be driven at slow speed in any appropriate manner.

10 At its discharge end, the feed conduit 17 is provided with an annular row of parallel discharge ports 19 and applied to the ported end of this conduit is a distributor head rotatably mounted on the conduit and including a hub 20, a disk 21 and 15 a plurality of substantially radial blades or vanes 22 secured to the face of the disk and disposed with their inner edges adjacent the periphery of the conduit for intercepting and directing the coating material, discharged from the ports 19 20 onto the pipe wall. The disk 21 may be rotated in any appropriate manner, as by a driving connection with the motor 15, shown by dotted lines in Figure 1. If desired, the rear end of the screw conveyor 18 may be provided with a suitable agitator or bladed wheel 23 for keeping the concrete 25 in motion and at its proper consistency. It is preferred that the inner edges of the blades terminate short of the conduit surface to form an 30 annular relief space or receiving chamber for the 35 material.

The discharge ports 19 are preferably disposed at an angle or obliquely to the horizontal in substantially the manner shown in Figure 4, whereby there is an overlapping of the ports to provide in 45 effect a continuous and uniform feed or discharge of the material from the conduit as well as a shearing and breaking up action of the mortar during its discharge. The distributing blades 22 intersect portions or segments of a plurality of 50 the ports 19, as seen by dotted lines in Figure 4, each blade section, for example, spanning the middle of one port and the opposing ends of adjoining ports, thereby effecting by this oblique 55 ported arrangement the desirable continuous feed

of the material in a substantially flat sheet to the revolving blades.

The tips or discharge ends of the distributing blades 22 are preferably serrated, saw-toothed or notched as indicated at 24, in Figures 2 and 5, for the purpose of effecting a breaking up of the material as it centrifugally leaves the blades to thereby effect a smoother and denser application of the coating material onto the pipe wall. As shown in Figure 3, the tip ends of the blades may be bent, as shown at 25, preferably in the same direction as that of the rotation of the distributing head. This construction has the effect of increasing the velocity of the coating material as it is discharged centrifugally from the blades, and this increased velocity affords a dense and compact application of the material onto the pipe wall.

At the rear end of the machine I have shown a suitable troweling device indicated generally by the numeral 26 which serves to smooth out the coating material after it has been applied to the pipe wall. I have also shown a distributing nozzle 27 for the purpose of treating the coating material with a curing fluid after it has been applied to the pipe wall and troweled.

I claim as my invention:

1. An apparatus for lining pipe walls and the like, comprising a feed conduit adapted for communication with a source of coating material and having an annular row of discharge ports therein, said ports being disposed obliquely to the conduit axis, and a revolving dispensing member including intercepting blades disposed in operative communicating relation to and covering a plurality of said discharge ports simultaneously for receiving and discharging the material centrifugally therefrom onto the pipe wall.

2. An apparatus for lining pipe walls and the like, comprising a feed conduit adapted for communication with a source of coating material and having an annular row of discharge ports therein, said ports being disposed obliquely to the conduit axis in substantially parallel relation and with their ends overlapping portions of adjoining ports to provide a continuous discharge of material therethrough, and a revolving dispensing member disposed in operative communicating relation to said ports for receiving and discharging the material centrifugally therefrom onto the pipe wall.

3. An apparatus for lining pipe walls and the like, comprising a feed conduit adapted for communication with a source of coating material and having an annular row of discharge ports therein, said ports being disposed obliquely to the conduit axis, and a revolving dispensing member disposed in operative communicating relation to said discharge ports and including substantially radial blades having their inner edges disposed adjacent the periphery of the feed conduit and in intersecting relation to a plurality of its ports

simultaneously, the free edges of said blades being serrated.

4. An apparatus for lining pipe walls and the like, comprising a feed conduit adapted for communication with a source of coating material and having an annular row of discharge ports therein, said ports being disposed obliquely to the conduit axis, and a revolving dispensing member disposed in operative communicating relation to said discharge ports and including substantially radial blades having their inner edges disposed adjacent the periphery of the feed conduit and in intersecting relation to a plurality of its ports simultaneously, the outer ends of said blades being laterally bent in a direction corresponding to the direction of rotation of the dispensing member.

5. An apparatus for lining pipe walls and the like, comprising a feed conduit adapted for communication with a source of coating material and having an annular row of discharge ports therein, said ports being disposed obliquely to the conduit axis, and a revolving dispensing member disposed in operative communicating relation to said discharge ports and including substantially radial blades having their inner edges disposed adjacent the periphery of the feed conduit and in intersecting relation to a plurality of its ports simultaneously; the outer ends of said blades being laterally bent in a direction corresponding to the direction of rotation of the dispensing member, and having their free edges serrated crosswise of the blades.

6. An apparatus for lining pipe walls and the like, comprising a feed conduit adapted for communication with a source of coating material and having an annular row of discharge ports therein, and a revolving dispensing member disposed in operative communicating relation to said discharge ports for receiving and discharging the material centrifugally therefrom onto the pipe wall, said dispensing member including substantially radial blades disposed substantially transversely to the plane of its rotation and having their inner edges disposed adjacent the periphery of the feed conduit to intercept the material discharged through said ports and having their outer free edges serrated crosswise of the blades.

7. An apparatus for lining pipe walls and the like, comprising a feed conduit adapted for communication with a source of coating material and having discharge ports therein, and a revolving dispensing member in operative relation to said ports and including substantially radial blades disposed substantially transversely to the plane of its rotation and having their inner edges disposed adjacent the conduit ports and having means extending transversely across their outer edges for breaking up the material as it is discharged from the blades.

ALBERT G. PERKINS.
